UNITED STATES PATENT OFFICE

LEE HALL, OF CHICAGO, ILLINOIS, ASSIGNOR TO FEDERAL ELECTRIC COMPANY, INC., OF CHICAGO, ILLINOIS, A CORPORATION OF NEW YORK

SIGN

Application filed June 19, 1926. Serial No. 117,033.

This invention relates to certain novel improvements in illuminated signs and consists of the matters herein described and more particularly pointed out in the appended claim.

5 The invention relates specifically to what are known as shadow signs, in which an opaque letter, cut out of sheet material, is supported in front of a white background and by means of illumination within the sign 10 body is caused to present the letter to the observer as a sharp, black shadow against the relief of the background.

15 The object of the present invention is to provide a sign of the kind which is of cheap parts are all readily and easily assembled and in which the background member, the reflectors, and illuminating devices are disposed in such fashion as to produce a superior and 20 improved result.

The many advantages of the invention will appear more clearly as I proceed with my specification.

In the drawings:—

25 Fig. 1 is a view representing a front elevation of an electrically illuminated sign made in accordance with my invention;

Fig. 2 is a view representing a horizontal section through the sign in a plane indicated 30 by a line 2—2 of Fig. 1;

Fig. 3 is a view representing on an enlarged scale a vertical section through the sign;

Fig. 4 is a detail view representing on an 35 enlarged scale one of the supporting rods for the sign letters and its means of attachment to the background member and to the letter respectively;

Fig. 5 is a perspective view of one of the 40 letters with its supporting rod.

In illustrating the invention, I have shown it as embodied in a double face sign, with letters appearing on both faces of the sign; but it will be obvious that it is equally applicable to single face signs, wherein the letters appear only on one face of the sign.

Referring now to that embodiment of the invention illustrated in the drawings:—10 indicates the sign body. Said body is preferably made of sheet metal and comprises (in

the case of a double face sign) two spaced face plates 11—11 and an open elongated frame 12 consisting of top and bottom members 13, 13 and of end members 14, 14, all attached together in any suitable manner to provide a rigid, sign-body structure. Each face plate has an elongated opening 15, preferably defined as in the drawings by a suitable border 16 which may be painted or stamped in the face plate along the edge of said opening. 17 indicates a plurality of letters supported in the said opening 15. The letters 17 are of less height than the height of the opening 15 and are supported by the sign body, as will presently be described, in a vertical plane near but somewhat back of the plane of the face plate 10.

In a vertical plane spaced back of the plane of the letters 17 and (in the case of a double face sign as illustrated herein) midway between the planes of the two face plates 11 is supported a background member 18. Said member is preferably made of sheet steel and by means of paint or enamel is provided with a bright, white, reflecting surface on both faces. The background plate 18 extends the length of the sign body and is secured at its ends by means of suitable flanges or otherwise to the end plates 14, 14 of the sign body. Said plate is of somewhat greater vertical height than the letter space openings 15 in the face plates 11 and thus extends well above and below the level of the tops and bottoms of the letters 17.

19, 19 indicate elongated, transversely parabolic reflectors at the top and the bottom of the sign body. Said reflectors extend the length of the sign body and are supported therein in any convenient manner with their edges closed against the inner surfaces of the face plates 10 at their margins defining the letter space openings 15. 20 indicates a plurality of lamps located in rows running the length of the sign body and placed respectively at the top and bottom 95 of the same with their centers of illumination in a line respectively below (in the case of the top lamps) and above (in the case of the bottom lamps) the focal axis of the associated reflector 19. 21 indicates the focal 100

axis of the reflectors and 22 indicates the line of the centers of illumination of the lamps. By this arrangement, the rays of light from the lamps, instead of being reflected in parallel vertical planes as would be the case if the foci of the reflectors and the centers of illumination of the lamps coincided, are in parallel planes inclined towards the plane of the background member 18, as indicated 5 by the dotted lines. Since the rays are parallel, the faces of the member 18 are evenly illuminated from top to bottom.

To further provide for even illumination over the entire extent of the faces of the 15 background member, it is preferred to get all of the illumination indirectly from the reflectors. To this end arcuate reflectors 23, 23 are fixed at the top edges of the background plate 18 in positions to block the 20 downwardly directed light rays of the lamps 20 and to throw them back against the parabolic reflectors 19.

The letters 17 are cut from sheet metal 25 and are painted black or some other dark color. Each letter is supported by one or more rods or pins 24 from the background plate 18. Each rod 24 is provided at its end with a threaded recess 25 and the letter 17 has a suitable aperture 26 for screws 27 by 30 means of which it is secured to the end of a rod 24. The background member 18 is provided with a plurality of apertures horizontally opposite the associated apertures in the letter plates and the inner ends of the 35 pins are secured to the plate 18 by like screws 27 taking through said apertures. Thus are several letters 17 comprising the sign are supported by the background plate 18.

40 The result and effect produced by the construction thus described will be apparent to those familiar with the art. The black letters will stand out in marked contrast against the evenly illuminated, brilliant, white faces of the background member 18, said faces appearing through the openings in the cut out letter and sharply defining said openings no matter how small they may be. The letters will thus appear as sharply defined black 45 shadows on the white background plate 18.

50 If desired one set of lamps may be eliminated and a fairly good result may be produced. Again only one reflector and its associated row of lights, namely that at the top or that at the bottom, may be used and the other reflector and its associated row of lights may be omitted.

The sign comprises few parts and is manifestly easily and readily to be assembled. 55 The open spaces between the letters and between the supporting rods or pins 24 make it possible to conveniently get at the faces of the background member 18 and at the reflecting surfaces of the reflectors for the 60 purpose of cleaning them.

I claim as my invention:—

An illuminated sign comprising, a sign body including an open frame, face plates on opposite sides of said frame, a background member located in said body substantially midway between and parallel to said face plates, each face plate having a letter space opening opposite said background member, cut out letters supported within said letter space, lamps supported in said sign body in the plane of said background member and located respectively above and below said background member, parabolic reflecting devices at the top and bottom of said sign body placed with their focal axes in the plane of said background member and respectively above and below the center lines of illumination of said rows of lamps, and auxiliary reflectors at the top and bottom of said background member adapted to block the direct light from said lamps to the faces of said background member.

In testimony that I claim the foregoing as my invention, I affix my signature this 10th day of June, 1926.

LEE HALL.
